UNITED STATES PATENT OFFICE.

THOMAS W. SYNNOTT, OF WENONAH, NEW JERSEY.

DESIGN FOR A LAMP-GLOBE.

SPECIFICATION forming part of Design No. 31,968, dated December 12, 1899.

Application filed October 27, 1899. Serial No. 734,889. Term of patent 14 years.

To all whom it may concern:

Be it known that I, THOMAS W. SYNNOTT, a citizen of the United States, residing at Wenonah, in the county of Gloucester, State of New Jersey, have invented and produced a new and original Design for a Lamp-Globe, of which the following is a specification, reference being had to the accompanying drawings, forming part thereof.

10 The leading feature of my design for a lamp-globe is a globe having a substantially uniform interior diameter and provided with longitudinally-extending internal flutes.

Figure 1 represents a vertical sectional view 15 of a lamp-globe embodying my design. Fig. 2 represents a section on line $x-x$, Fig. 1.

Fig. 3 represents a perspective view of the globe.

In the drawings, A designates a lamp-globe having its interior surface B of substantially uniform diameter, said surface being provided with longitudinally-extending internal flutes C.

Having thus described my invention, what I claim as new, and desire to secure by Letters Patent, is—

The design for a lamp-globe, substantially as shown and described.

THOMAS W. SYNNOTT.
